UNITED STATES PATENT OFFICE.

PHINEAS F. KING, OF ST. LOUIS, ASSIGNOR TO HIMSELF AND ALFRED S. WOLF, OF KANSAS CITY, MISSOURI.

NAIL-EXTRACTOR.

SPECIFICATION forming part of Letters Patent No. 313,599, dated March 10, 1885.

Application filed December 30, 1884. (No model.)

To all whom it may concern:

Be it known that I, PHINEAS F. KING, a citizen of the United States, residing at St. Louis, and State of Missouri, have invented a new and useful Improved Nail-Extractor, of which the following is a specification.

My invention relates to the class of nail-extractors; and it consists of an improved instrument, implement, or tool, in the use whereof of the extraction of nails, spikes, and fastenings of a similar nature can be accomplished in the most quick, decisive, and noiseless manner without injury to the nails or fastenings, and which, further, as a tool shall possess the advantages of being simple, cheap, and durable, and in its operation most effective and reliable. I attain these objects by the mechanism illustrated in the accompanying drawings, in which—

20 Figure 1 is a perspective view of the entire tool. Figs. 2, 3, 4 are views designed to illustrate the successive positions or movements the tool is made to assume during the operation of withdrawing the nail. Thus Fig. 2 represents the tool as applied in position preparatory by its claws to nip or grasp the nail. In this position the claws and fulcrum-plate are in their highest position. Fig. 3 shows the tool in the position it assumes when its 30 claws have been drawn completely under the head of the nail. In this position the claws and fulcrum-plate are in their lowest position. Fig. 4 represents the tool in the final position it assumes to extract the nail; and Fig. 5 is a 35 plan view taken on line 5 of Fig. 3.

Similar letters refer to similar parts throughout the several views.

A is the hand-lever. This at its lower end has the crook or curved offset at A', terminating in claws at B, in manner indicated in Figs. 1, 2, 3, 4. Between the claws exists the open space b, which permits the claws to be drawn under the nail to grasp its head and retain the nail between the jaws. This open space is 40 wider at the front than the rear, (see Figs. 1, 5,) to adapt the claws to take hold of different sizes of nails. Also, the outer faces at b' b² of the claws I make a taper or to bevel, as shown in Figs. 1, 2, which taper facilitates 45 the claws entering under the head of the nail,

and at same time to crease or cut the surface as slightly as possible; also, the claws are tapered when viewed in plan view, (see letters b³ b⁴ in Figs. 1, 2, 5,) by means whereof the claws retain their hold upon the nail during the various positions the tool is made to assume, as will hereinafter be described. 55

C is the fulcrum-plate. This has its bearing edge formed with teeth c, to take a better hold and retain a firm bearing at that point. 60 The fulcrum-plate C is forked or slotted, so that its two opposite sides at c' c² can be pivoted to the crook of the hand-lever. (See Figs. 1 and 5.) For this purpose a pin, c³, passes through said parts and virtually hinges 65 said fulcrum-plate to said lever behind its jaws. (See figures.) At c' is a shoulder to stop the fulcrum-plate or the hand-lever when turned. A spring, c⁴, surrounds the pivotal end and is interposed between the sides of the 70 fulcrum-plate and crook of the lever. Said spring automatically restores the fulcrum-plate to its position.

The parts being thus constructed and arranged, the operation and use of the tool are as 75 follows: In first applying the tool the operator places same with relation to the nail or fastening to be extracted as shown in Fig. 2. In this position the hand-lever is forward, its claws and fulcrum-plate are in their highest 80 position, and the nail-head is near the front entrance of the claws. The operator next raises the hand-lever to assume the vertical position shown in Fig. 3. This action lowers the claws, also lowers the fulcrum-plate in manner indicated in said figure. Here it will be noted that in the adjustable action of the fulcrum-plate the head of the nail or fastening draws the claws under the latter, retaining their hold upon the nail until the fulcrum-plate has 85 been brought to its lowest position. To finally extract the nail or fastening, the operator draws back the hand-lever to the position shown in Fig. 4, which action extracts the nail in raising the claws, the lower end of the 90 fulcrum-plate serving as the bearing for this lift movement. The bearing of the fulcrum-plate at c remains the same during all the 95 positions the tool is made to assume.

My improved tool is noiseless in its oper- 100

ation. It decisively takes hold of the fastening, and by its leverage renders the extraction of the nail or fastening a very simple and easy one.

5 As apparent, the tool can be made large or small, according to the uses it is to be applied, and is therefore adapted for a wide range of purposes.

What I claim is—

10 1. The combination, with the hand-lever having the crook or offset A', terminating in claws B, the pivoted fulcrum-plate C, and interposed spring c⁵, substantially as and for the purposes set forth.

2. In a tool for extracting nails, &c., a hand-lever having the crook or offset A', terminating with claws B, made to have the bevel or tapering faces at b b' b² b³, the fulcrum-plate C, pivoted at c⁴, the shoulder at c⁴, and spring c⁵, all combined to operate in the manner and 15 20 for the purposes set forth.

In testimony of said invention I have hereunto set my hand.

PHINEAS F. KING.
